UNITED STATES PATENT OFFICE

154,702

DESIGN FOR A CHILD'S TOILET SEAT

Oliver W. Partain, Tulsa, Okla.

Application January 2, 1948, Serial No. 143,517

Term of patent 14 years

(Cl. D4—5)

To all whom it may concern:

Be it known that I, Oliver W. Partain, a citizen of the United States, residing at Tulsa, in the county of Tulsa and State of Oklahoma, have invented a new, original, and ornamental Design for Child's Toilet Seat, of which the following is a specification, reference being had to the accompanying drawing forming part thereof.

Fig. 1 is a perspective view of a child's toilet seat.

Fig. 2 is a plan view.

Fig. 3 is a bottom view.

Fig. 4 is a front elevation.

Fig. 5 is a section on the line 5—5, Fig. 2.

Fig. 6 is a section on the line 6—6, Fig. 2.

I claim:

The ornamental design for a child's toilet seat,
OLIVER W. PARTAIN.
